UNITED STATES PATENT OFFICE

WALTER D. TEAGUE, OF FOREST HILLS, NEW YORK, ASSIGNOR TO TURNER GLASS CORPORATION, OF TERRE HAUTE, INDIANA, A CORPORATION OF INDIANA

DESIGN FOR A JAR OR SIMILAR CONTAINER

Application filed January 27, 1930. Serial No. 34,312. Term of patent 14 years.

To all whom it may concern:

Be it known that I, WALTER D. TEAGUE, a citizen of the United States, residing at Forest Hills, in the county of Queens and State of New York, have invented a new, original, and ornamental Design for a Jar or Similar Container, of which the following is a specification, reference being had to the accompanying drawing, forming part thereof.

Figs. 1 and 2 are elevations of a container showing my new design, the two figures being taken from slightly different view points.

Fig. 3 is a horizontal section looking down, taken substantially on the line 3—3 of Figure 1.

Fig. 4 is a bottom plan of the container shown in Figures 1 and 2.

I claim:

The ornamental design for a jar or similar container as shown.

WALTER D. TEAGUE.
